DESIGN FOR A RUG.

UNITED STATES PATENT OFFICE.

ERNEST H. BENNETT, OF EAST ORANGE, NEW JERSEY, ASSIGNOR TO JOHN BROMLEY & SONS.

DESIGN FOR A RUG.

SPECIFICATION forming part of Design No. 20,976, dated August 11, 1891.

Application filed February 2, 1891. Serial No. 379,924. Term of patent 3½ years.

To all whom it may concern:

Be it known that I, ERNEST H. BENNETT, a citizen of the United States of America, residing at East Orange, in the county of Essex 5 and State of New Jersey, have invented a certain new and original Design for a Rug, of which the following is a specification, reference being had therein to the accompanying drawing.

10 My invention relates to the surface ornamentation of rugs; and it consists of the design therefor, which is fully illustrated in the accompanying photographic drawing, its leading features being a rectangular field center 15 of net-work lines surrounded by a border-

like arrangement of isolated fanciful figures, and within the field center a large figure of the same character as those forming the border, said figure being surrounded on its edges by a floral and leaf-like ornamentation. 20

I claim as my invention—

The design for a rug, substantially as shown and set forth.

In testimony whereof I affix my signature in presence of two witnesses.

ERNEST H. BENNETT.
